UNITED STATES PATENT OFFICE.

ROLLAND J. CANTON, OF LYNN, MASSACHUSETTS.

BOTTLE-CAPPING AND WIRE-REMOVING MACHINE.

1,381,278.

Specification of Letters Patent. Patented June 14, 1921.

Application filed February 19, 1920. Serial No. 359,967.

To all whom it may concern:

Be it known that I, ROLLAND J. CANTON, a citizen of the United States, and resident of Lynn, in the county of Essex and State of Massachusetts, have invented an Improvement in Bottle-Capping and Wire-Removing Machines, of which the following description, in connection with the accompanying drawings, is a specification, like letters 10 on the drawings representing like parts.

My present invention relates to bottle capping machines, and more particularly to a combined bottle capping and wire removing machine adapted for use on milk bottles and 15 the like.

In bottling high grade milk at the present day, it is customary to not only cap the bottle with the usual wax paper cap or disk, but also to further protect the contents of the 20 bottle by placing a paper cup over the top of the bottle and hold such cup in place by a crimped metal ring.

With new bottles, the above method of 25 procedure is comparatively simple and easily carried out. The main difficulty is in carrying out the method on bottles that have been previously cupped and which therefore, after washing, must be refilled with milk 30 and then recapped and recupped. When the milk is to be used, the outer cup and inner cap are removed, the crimped wire however, being left on the neck of the bottle. It is, of course, necessary that this 35 wire ring be removed before the bottle can be recupped, and heretofore this has been done by an operator grasping a bottle in both hands and snapping the wire ring apart over a hook fastened to a bench or other convenient support. This operation is expensive 40 as it not only occupies the time of a man, but results in considerable breakage, the breakage averaging about twenty per cent. Also, this operation is dangerous, as due to 45 the large breakage, the operator is frequently injured by fragments of glass.

I have obviated the defects above noted by devising automatic wire removing means that operates in conjunction with a bottle 50 capping machine, such for example, as the capping machine known as the Milwaukee capper, and described and claimed in Patent No. 1,040,453 and dated October 8, 1912.

My invention is capable of being used as a 55 separate machine, in which event the removal of the wire from the bottles is a sepa-

rate operation, or it may be used in combination with the capping machine, as above described, and as this use speeds up the work of preparing the filled bottles for shipment 60 and is more economical, I prefer to use it in this manner.

The principal object of my invention therefore, is an improved device for removing wire rings from milk bottles and the 65 like.

Another object is the provision of an improved combined bottle capping and wire removing machine.

In the accompanying drawings illustrating 70 the preferred embodiment of my invention,

Figure 1 is a rear elevation of a capping machine embodying my invention,

Fig. 2 is a plan view,

Fig. 3 is a sectional side elevation, showing 75 a bottle in position to be operated on,

Fig. 4 is a sectional side elevation showing the bottle after the capping operation and 80 with the wire ring removed,

Fig. 5 is a side elevation of the improved means for removing the wire rings, and

Fig. 6 is a front elevation of such improved means.

Referring to the drawings, 10 and 11 85 designate supporting posts, extending upwardly from a suitable platform (not shown) and adjustably mounted on said posts 10 and 11 is a bracket 12, clamping screws 13, at either side thereof providing means for clamping such bracket in adjusted position.

Slidably mounted in a vertical centrally located bearing 14 in the bracket 12 is a 95 shaft 15, which extends upwardly from the bracket 12 a suitable distance, and downwardly to an operating treadle (not shown). Fastened to the top of the shaft 15 by a pin 16 is a holding bracket 17, an additional fastening means 18 engaging in a transverse slot in the shaft and held in position by bolt 19 and screw 20. Laterally extending arms 21 on the bracket 17 carry depending rods 23 slidable therein and prevented from falling out of said arms 21 by collars 24 pinned to the rods. Intermediate the ends of each rod 23 is a bracket 25 with laterally extending arms 26, these brackets being pinned to the rods 23, as shown in Figs. 3 and 4. On 100 the rods 23, between the upper face of the bracket 25 and the lower face of the bracket

110

21 is a coiled spring 27, the purpose of which will be hereinafter described. Slidably mounted on each of the rods 23 is a frame 28 provided at its lower end with a circular chamber 29, a capping head 30, attached to the lower end of the rod 23 by screw 31, fitting loosely in said chamber, and predetermining the lower limit of movement of the frame 28 on such rod. At one side of the frame 28, or to the right as viewed in Figs. 3 and 4, is a cap receptacle or magazine 32, which is parallel to the rod 23, and is adapted to hold a plurality of caps 53.

Attached to the lower face of the frame 28, but spaced apart therefrom a distance slightly greater than the thickness of a bottle cap 53, is a member having a conical recess 33 in alignment with the chamber 29 and of such size and shape as to readily engage with and center the top of a milk bottle, and a tapered extension or cap supporting platform 34 which extends beneath and beyond the cap receptacle, above referred to. This chamber is attached to the frame 28 in any convenient manner, as by screws 35. On each side of the frame 28 are guides 36 which engage in guideways 37 in the adjustable bracket 12.

Mounted for sliding movement longitudinally of the cap supporting platform 34 are cross-heads 38 provided with top plates 39 of dimensions that permit them to move between the upper face of the member comprising the recess 33 and the cap supporting platform 34, and the lower face of the frame 28, the end of such plate 39 being rounded, as shown at 40, to more readily engage with and feed a cap 53 from the cap receptacle 32 to the chamber 29. Links 41 are pivotally mounted at one end on each side of the cross-heads 38, the other end of said links being pivotally attached to one end of one of the arms of the bell crank levers 42, which levers are pivotally mounted on opposite sides of the cap receptacle 32. The other arms of the bell crank levers 42 are provided with an elongated slot 43 in which works a stud 44 on one end of links 45, the other ends of which are pivotally mounted on the extremities of the laterally extending arms 26 of the bracket 25.

Pivotally mounted on the holding bracket 17 on the shaft 46 are depending articulated wire removing cutters 47, these cutters 47 being jointed at 48, the lower portion being curved and beveled, as shown at 49 and 50 respectively, a leaf spring 51 attached to the lower portion and having a screw 52 engaging with the upper portion to adjust the tension of such spring. These cutters 47 extend downwardly, being held in operative position by guideways in the adjustable bracket 12 and conical recess 33, the guideway in the recess 33 being such as to allow the lower or cutting end of the cutter 47 to

extend well into the recess, as shown in Figs. 3 and 4.

The operation of my invention is as follows, assuming that the mechanism is in the position shown in Fig. 4, a bottle having just been capped and the wire ring removed. The treadle (not shown), is operated to move the holding bracket 17 upwardly, carrying the frame 28 and associated parts, and the cutter 47, therewith. As the rods 23 move upwardly, the frame 28 remains stationary until the capping head 30 engages with the bottom of the chamber 29, and during this period the cross-head 38, through the linkage 42, 43, 45, moves the plate 39 longitudinally of the cap supporting platform 34, forcing the lower cap of the pile of caps in the receptacle or magazine 32 into the chamber 29, the spring 27 being compressed during this operation. Continued upward movement of the operating post 15 moves the conical recess 33 upward a sufficient distance to allow the capped bottle to be removed.

Ordinarily in practice, the bottles are supported on a rotatable table, and are supplied to the machine in pairs, but as this feature of the machine does not concern the present invention, it has not been described or illustrated. It is sufficient for the present purpose to know that at this stage of the proceedings an additional bottle or bottles are supplied to the machine and occupy the position with respect thereto shown in Fig. 3, the wire to be cut and removed being designated 55. The treadle (not shown) is now operated to lower the holding bracket 17 and parts carried thereby, the cutter 47 engaging with the upper side of the bottle, the spring 51 and joint 48 allowing and maintaining it in engagement with the bottle. As the frame 28 is lowered simultaneously with the cutter 47, the conical recess 33 engages with and holds the bottle in position, and further downward movement of the bracket 17 forces the curved and beveled end 49 and 50 of the cutter 47 between the ring 55 and the side of the bottle, cutting and breaking said ring and throwing it off from the bottle. Simultaneously the rod 23 forces the capping head 30 against the cap 53 in the chamber 29 and into the top of the bottle, as shown in Fig. 4. During the first part of the downward movement of the bracket 17, the spring 27 operates to return the cross-head 38 and plate 39 to the position shown in Fig. 3.

While I have shown and described the preferred embodiment of my invention somewhat necessarily in detail, it is to be understood that I may vary the size, shape, and arrangement of parts making up the device within considerably wide limits without departing from the spirit of the invention.

Having thus described my invention, what I claim as new and desire to secure by Letters Patent, is:—

1. In a machine of the class described, the combination of bottle capping means, and means for removing a wire cup holding ring from the bottle simultaneously with the operation of the bottle capping means.
  2. In a machine of the class described, the combination with bottle holding means, of a reciprocating cutter engaging with and movable with respect to the bottle, whereby to engage, cut, and remove used cup holding rings from the neck of the bottle.
  3. In a machine of the class described, the combination with bottle holding means, of a reciprocating cutter, guide means therefor, a tensioning device for adjusting the tension of the lower end of the cutter in its guide, said cutter engaging with and movable with respect to the bottle, whereby to engage, cut, and remove used cup holding rings from the neck of the bottle.
  4. In a machine of the class described, the combination with an articulated reciprocating cutter, guide means therefor, a tensioning device for adjusting the tension of the lower end of the cutter in its guide, said cutter engaging with and movable with respect to the bottle, whereby to engage, cut, and remove used wire cup holding rings from the neck of the bottle.
  5. In a machine of the class described, the combination of a pair of brackets, a plunger slidably supported in said brackets, a collar adapted to engage with and position a bottle
- in operative relation to said plunger, a cap supporting platform, a cap receptacle open at its lower end supported at a slight distance from said platform, a cap carrying slide supported on said platform, a reciprocating operating member connected with and adapted to support all of the movable members of the capper, means connected with said operating member dependent on the resistance of the bottle when the bottle is in place beneath said collar for moving said cap carrying slide back beneath the cap receptacle, preparatory to moving forward a cap as the preceding cap is being forced by the plunger into the mouth of a bottle, means actuated by the reverse movement of said actuating member for carrying a cap forward above a bottle as said plunger is raised, and means operating simultaneously with said plunger for automatically removing a used wire cup holding ring from the neck of a bottle.
6. In a machine of the class described, the combination of a reciprocating member, a bottle holding means, guideways, an articulated wire cutting device pivotally mounted on and reciprocable with said member, adjustable spring tensioning means for adjustably holding the cutting end of said cutting device in engagement with the outside of the neck of said bottle, whereby to engage, cut, and throw off from said bottle a used wire cup holding ring.

In testimony whereof, I have signed my name to this specification.

ROLLAND J. CANTON.
